UNITED STATES PATENT OFFICE

RAY E. DUNHAM, OF BEREAL, OHIO, ASSIGNOR TO THE DUNHAM COMPANY, OF BEREAL, OHIO, A CORPORATION OF OHIO

ROLLER PULVERIZER

Application filed February 23, 1928. Serial No. 256,131.

The present invention relates to roller pulverizers of the type shown in the Dunham Reissue Patent No. 13,921, of June 1, 1915, although it will be understood that the roller disks which more particularly form the novel features of the present invention are applicable to roller pulverizers generally, either single or double, and that the details of the framework and mounting shown serve rather to illustrate the applicability of the roller disks to pulverize generally than to impose particular limitations in the employment of such roller disks.

In roller pulverizers of the character commonly in use, it is the practice at the present time to provide either a single rank or two ranks of roller disks, each disk having a beveled edge formation, and the disks in union constituting in effect a corrugated roller or rollers, as the case may be, which pass over the ground and serve to cut, break up, and pulverize the clods or lumps of earth, leaving the surface of the field in a rigid or corrugated condition.

In the case of the present invention, the disks, instead of having truly circular beveled cutting edges, are given an undulatory edge formation which materially improves the cutting, crushing, and pulverizing qualities of the disks, and at the same time leaves the surface of the field in a distinctively different condition, in that the ridges or corrugations are of irregular rather than straight formation, which irregularity in the ridges and valleys formed in the field tends to better prevent any scouring action by the wind or by the downflow of water than in the case where the ridges and valleys run in a straight direction as has heretofore been customary in the case of fields which have been conditioned by a roller pulverizer of the ordinary type.

The invention further relates to certain structural peculiarities in the formation of the disks wherein the spokes on the opposite faces of the disk are arranged in staggered relation to one another which, in conjunction with the undulating formation, affords a stronger and more durable structural arrangement than has heretofore been employed.

Further objects and details will appear from a description of the invention in conjunction with the accompanying drawings wherein—

Figure 1 is a face view of one of the disks embodying the features of the present invention;

Fig. 2 is a sectional view taken on line 2—2 of Fig. 1;

Fig. 3 is a plan view of the disk mountings for a double roller pulverizer showing a front roller rank of straight-edged disks with a rear rank of the undulatory disks;

Fig. 4 is an end elevation of the same;

Fig. 5 is a plan view showing the employment of the undulatory disks in both ranks; and

Fig. 6 is a plan view showing the undulatory disks in the front rank with the straight-edged disks in the rear rank.

For purposes of illustration, the disks are shown in connection with a double roller pulverizer which comprises a tongue 10 and a seat 11 mounted thereon, which tongue serves to connect the front and rear cross bars 12 and 13 of the frame. Each end of the frame has a depending fixed bracket 14 which serves at its lower end for the pivoting of an oscillatory frame bar 15 having an upstanding lug 16 which receives a pivot bolt 17 for uniting the parts together. The oscillatory frame bars afford journals for a front axle 18 and a rear axle 18^a, which axles freely carry the disks which particularly form the subject matter of the present invention. It is not deemed necessary to further describe the frame arrangement which is shown merely for purposes of illustration and is of a character well understood in the art.

The disk of the present invention comprises a rim 19 which, in cross section, is of concavo-convex wedge-shaped formation, the rim walls being concave on the exterior, and merging together into a cutting edge 20, which, as best shown in Fig. 2, is of undulatory configuration around the periphery of the disk. With the disks standing vertically in operative position, the cutting edge will curve alternately toward one side and then toward the other side of the disks, so that as

a single disk is rolled over a field, it will produce an undulatory cut or groove in the surface conformable to the undulations in the periphery of the disk.

5 The disk is hollow, as shown, the interior configuration conforming substantially to that of the exterior, and the rim or periphery of the disk on each side terminates in a central opening 21 which is spanned on each side by a plurality of spokes 22, the inner ends of which merge into a hub 23. The arrangement of the spokes on each side of the wheel is such as to bring the spokes into staggered relation to one another, so that the support provided by the spokes will be more uniformly distributed around the periphery of the wheel than would be possible if the spokes on one side were in register with those on the opposite side.

20 As viewed from a given side of the disk, the outer ends of the spokes on that side merge into the rim, in each instance at a point where the undulations form a crest which most nearly approaches the points of connection 25 for the spokes. In other words, in each instance, the distance between the end of a spoke and the rim at that point is at a minimum, as will be noted from an inspection of Fig. 2. By reason of this fact, the configuration of the disk as a whole is one in which the degree of offset between the spokes and the cutting edge will in each instance be at a minimum, so that, with a given weight of 30 metal, greater strength and rigidity will be 35 afforded than is the case of disks of the type ordinarily employed in roller pulverizers.

The staggered arrangement of the spokes, in conjunction with the manner in which the spokes are united with the rim, is of special 40 importance in the present instance, in that the undulatory character of the cutting edge imposes a greater degree of lateral thrust 45 against the rim than is the case with disk wheels of the ordinary configuration in which straight line grooves are formed in the soil.

As illustrated, the present disks may be used on both roller gangs as in Fig. 5, or on the front gang only as in Fig. 6, or on the rear gang only as in Fig. 3. Where soil conditions are such as to require a maximum amount of pulverizing action, it may be desirable to provide both of the gangs with 50 disks of the undulatory character. Where it is desired to condition the field with straight 55 grooves and ridges, the rear gang may be provided with disks of the ordinary type, and conversely where it is desired to finish the field with irregular corrugations, the rear gang of disks alone may be of the undulatory 60 type.

In operation with the undulatory roller disks, the cutting edges will sink into the surface soil to the degree represented by the grooves between adjacent disks, and as the 65 implement advances, the clods or lumps of

earth will be cut by the cutting edges and displaced laterally more or less by the undulations in the cutting edge and by the wedge-shaped configuration, so that the lumps of soil will be rolled over, abraded, laterally 70 displaced, and packed down in a finely divided and thoroughly compacted condition.

In view of the fact that the undulatory disks are loosely or freely mounted upon the shaft or shafts which carry them, they are 75 free to roll individually, so that in use there will be no uniformity in the alignment of the undulations of adjacent disks, with the result that instead of conditioning a field with uniformly extending ridges or corrugations 80 equally spaced from one another, the adjacent ridges will, in a more or less haphazard manner, approach and recede away from one another with no regularity in the spacing, which gives to the soil surface a non-uniform 85 finish in contradistinction from the uniformly corrugated straight ridged surface left by the passage of a roller pulverizer having disks of the usual type.

However, where it is desired to secure such 90 uniformity, the older type of disks may be provided on the rear gang as in Fig. 6, in which case the front rank or gang of undulatory roller disks will be relied upon to perform the greater measure of crushing and 95 depression, while the rear rank or gang will be relied upon to smooth out and uniformly corrugate the surface, leaving the ridges in parallel lines.

The disks of the present invention are of 100 a type to effect a greater displacement and disturbance of the soil than can be secured by the use of disks having non-undulatory cutting edges, which increased displacement under the conditions indicated, result in a 105 greater degree of abrasion and disintegration of the soil, which is highly desirable in the preparation of a seed bed.

The arrangement is one which permits the disks of the present invention to be substituted for or used in conjunction with roller disks of the usual character on all machines now on the market, so that a farmer may employ combinations of disks in a way which will best meet the soil conditions encountered 110 in various localities.

I claim:

1. A roller pulverizer disk having a concavely beveled periphery forming a circumferentially extending laterally undulating cutting edge, the roller disk being hollow and provided on each side with spokes merging into a centrally disposed hub, the spokes on one side being arranged in staggered relation with respect to the spokes on the other side, substantially as described.

2. A roller pulverizer disk having a concavely beveled periphery forming a circumferentially extending laterally undulating cutting edge, the faces of the periphery on 130

each side of the cutting edge being concavely curved, the roller disk being hollow and provided on each side with spokes merging into a centrally disposed hub, the spokes on one side being arranged in staggered relation with respect to the spokes on the other side, substantially as described.

3. A roller pulverizer disk having a concavely beveled periphery forming a circumferentially extending laterally undulating cutting edge, the roller disk being hollow and provided on each side with spokes merging into a centrally disposed hub, the spokes on one side being arranged in staggered relation with respect to the spokes on the other side, the outer ends of the spokes in each instance merging into the periphery at a point in alinement with the adjacent crest of one of the undulations of the cutting edge, substantially as described.

4. A roller pulverizer disk having a concavely beveled periphery forming a circumferentially extending laterally undulating cutting edge, the faces of the periphery on each side of the cutting edge being concavely curved, the roller disk being hollow and provided on each side with spokes merging into a centrally disposed hub, the spokes on one side being arranged in staggered relation with respect to the spokes on the other side, and the outer ends of the spokes in each instance merging into the periphery at a point in alinement with the adjacent crest of one of the undulations of the cutting edge, substantially as described.

5. In a roller pulverizer, the combination of a frame, an axle carried by the frame, and a plurality of laterally adjacent contacting roller disks freely mounted on the axle, each of the disks being provided with a concavely beveled periphery having a laterally undulating cutting edge, substantially as described.

6. In a roller pulverizer, the combination of a frame, front and rear axles carried by the frame, and roller disks freely mounted upon the front and rear axles in laterally adjacent and contacting relation, one of the groups of roller disks being provided with concavely beveled peripheries having laterally undulating cutting edges, substantially as described.

7. In a roller pulverizer, the combination of a frame, front and rear axles carried by the frame, and roller disks freely mounted upon the front and rear axles in laterally adjacent and contacting relation, both of the groups of roller disks being provided with concavely beveled peripheries having laterally undulating cutting edges, substantially as described.

RAY E. DUNHAM.
